UNITED STATES PATENT OFFICE.

EVAN T. STOVER, OF CHICAGO, ILLINOIS, ASSIGNOR TO JOSEPH STOVER
AND GEORGE W. ROBERTS, BOTH OF SAME PLACE.

FACE-PROTECTOR.

SPECIFICATION forming part of Letters Patent No. 331,340, dated December 1, 1885.

Application filed January 12, 1885. Serial No. 152,692. (No model.)

To all whom it may concern:

Be it known that I, EVAN T. STOVER, residing at Chicago, in the county of Cook and State of Illinois, and a citizen of the United States, have invented a new and useful Improvement in Face-Protectors, of which the following is a full description, reference being had to the accompanying drawings, in which—

Figure 1 is a perspective of the metal frame. 10 Fig. 2 is a front elevation of the frame; Fig. 3, an end view of the frame, looking at the bottom of Fig. 2, the position of the nose when the protector is in use being indicated by dotted lines. Fig. 4 is an inside view of the completed protector. Fig. 5 is a section at line *x* of Fig. 4, showing also in dotted lines the position of a face behind the protector.

My invention relates to that class of protectors designed for use in cold weather; and 20 its objects are to provide a light metal frame to support the protecting material, and to provide full protection for the face and leave a suitable breathing - passage, which I accomplish as illustrated in the drawings, in which—

25 A represents a light metal frame, which, as shown, is made of two pieces of wire, one of which forms the main part of the entire frame.

b is a cross-bar made of a separate piece. The bars *b c d* are curved to correspond with 30 the curve of the face. The part *e* extends down in front of the chin, and the part *f* extends down from the bar *d* some distance in front of *e*, leaving a passage between *e* and *f*, through which air can pass to and from the mouth and 35 nose.

A convenient way to make the frame is to commence at the point *i*, the wire then at that point being straight, then forming first the part *e*, then passing up on one side of the 40 frame, then across to the opposite side, forming the upper bar, *c*, then down to the point *i*, then half-way across the front to the point *j*, there bending the wire back upon itself, then forming the part *f* and locking the wire 45 upon itself at *j*, then completing the cross-bar *d*, making the hook at *k*, and bending over the end of the wire at *i* in the form of a hook.

B, Fig. 4, represents the face - protector proper, which may consist of an outside piece 50 of fine rubber cloth with an inside lining, *g*, of

flannel, the two being secured by stitching to the metal frame, but not to the part *f*.

h is a covering for the mouth, which extends down in front of the chin. It is secured to the cross-bar *b* and passes down over the part *f*, 55 which supports it and holds it away from the face, so that there will always be an open passage for breathing. (Indicated by arrows in Fig. 5.)

For the protection of the ears I provide extensions *l*, which may have openings in them covered with hair-cloth or wire-cloth *m*.

n is a piece of fine wire-cloth secured to the frame so as to come over the eyes when in use. This wire-cloth will protect the eyes from snow 65 and dust without materially obstructing the vision. The flap *h*, I make of rubber cloth and line it with the same material, instead of with flannel, to prevent the accumulation of moisture. The space between the bars *b* and 70 *d* is covered with the flannel, but need not be covered with the outside cloth, because the upper end of the flap *h* covers this portion of the frame and lining.

The protector can be readily folded into a 75 small compass no greater than the size of the frame, and then can be easily carried.

I thus provide complete protection for the entire face and the ears against cold, and also make ample provision for allowing air to pass 80 to and from the lungs without exposing any part of the face.

In Fig. 3 I have indicated in dotted lines the position which the nose will occupy when the protector is in place. If desired, the space 85 outside of the nose and between the part *d* and the parts *e e'* may be closed by a piece of cloth, to prevent the breath from passing up by the side of the nose.

The protecting material *B* is to be large 90 enough to cover the entire face, and much larger than the metal frame. In preparing *B* an opening is to be cut for the eyes, and another part is also to be cut out for the mouth, a portion of the chin, and lower part of the nose, 95 and this piece is to be so cut out that the edges from which it is taken can be sewed to the bar *d* and to the parts *e e'*. The protecting material is then to be sewed to the vertical part *a* of the frame, also to the cross-bars *c b d*, also 100

to the parts *e e'*. The flap *h* is then to be sewed in place.

The dotted line *r* in Fig. 4 indicates the position of the lower part of the flap *h*. The 5 same letter, *r*, is placed upon the lower edge of the flap in Fig. 5.

The protector can be secured to the head by means of straps.

What I claim as new, and desire to secure by 10 Letters Patent, is—

1. In a face-protector, a metal frame consisting of the vertical bars *a*, the bars *b c d*, curved to correspond to the contour of the face, a downward extension, *e*, to embrace the 15 chin, and an extension, *f*, projecting down-

wardly in front of and at a little distance from the extension *e*, substantially as described.

2. In a face-protector, a metal frame having an extension, *e*, for embracing the chin, and an extension, *f*, projecting downwardly in 20 front of and at a little distance from the extension *e*, in combination with protecting material secured to the frame, and a flap, *h*, secured at its upper end to the frame and extending over the extension *f*, substantially as 25 and for the purpose described.

EVAN T. STOVER.
